ROTARY FOR WELL DRILLING

August R. Maier, Dallas, Tex., assignor to Oil Well Supply Company, Dallas, Tex., a corporation of New Jersey

Application November 22, 1934, Serial No. 754,319

5 Claims. (Cl. 184—6)

My invention relates to a rotary for drilling wells such as petroleum wells.

Rotaries are employed in well drilling to drive a hollow drill stem extending into the well being drilled and comprise a rotatable table for engaging or gripping the drill stem and a driving gear for rotating the table. Owing to the conditions under which these rotaries operate, they are frequently splashed or covered with mud and 10 the gearing and bearings on which the rotaries rotate must, therefore, be carefully enclosed to protect them from contact with mud. As the drilling operations and, therefore, the rotary are run substantially continuously during the drilling 15 of the well, except for slight interruptions, opportunities are not afforded to inspect the interior of the rotary or to see that it is properly supplied with lubricants. It is, therefore, essential that loss of lubricant during a drilling operation be reduced to a minimum or entirely 20 eliminated.

My invention provides a rotary in which the bearing and driving elements are enclosed and adequately protected from entrance of mud or other foreign matter and in which the lubricant 25 is circulated to the gears and bearings from a reservoir and back to the reservoir without substantial loss.

The various features of my invention are illustrated in the accompanying drawings, in which—

Fig. 1 is a plan view of a rotary embodying my invention.

Fig. 2 is a vertical section of the rotary taken on the line 2—2 of Fig. 1.

Fig. 3 is a vertical section of a detail of the rotary illustrating the path of circulation of the oil or lubricant.

In the accompanying drawings the invention is illustrated by way of example as applied to a 40 rotary having a base 10 and a table 11 rotatably supported on the base by means of anti-friction bearings 12. The base 10 has an upstanding outer wall 13 extending upwardly to the under face of the table 11, and an inner wall 14 upon 45 which the bearing 12 is supported and forms between the inner and outer walls an annular oil or lubricant channel or reservoir 15. The inner wall 14 also has a depending flange 16 carrying a bearing liner 17 through which there extends 50 downwardly from the table 11 an inner collar 18. The upper base of the table 11 extends outwardly to the upper edge of the wall 13 and slidably joins the latter in an interlocking seal 19 to prevent the inflow of water or mud.

55 This seal is still further protected by an annu-

lar angle apron 20 mounted on the wall 13 and having a depending flange 21. The table 11 carries inner spiders 22 and 23 which serve to grip and hold a drill pipe extending downwardly therethrough.

An extension 24 from the outer wall 13 carries bearings 25 in which is mounted a driving shaft 26 provided at its projecting end with a driving sprocket 27. The extension 24 also provides a lubricant supply 28 for the bearings 25. The 10 shaft 26 extends through the wall 13 and projects above the reservoir 15. A bevel gear 29 is keyed onto this projecting end of the shaft 26 in position to dip into the lubricant carried in the reservoir 15 and also to engage an annular bevel 15 gear 30 mounted on the lower surface of the table 11. As the shaft 26 is driven by the sprocket wheel 27, it rotates the gear 29 and with it the gear 30 and table 11 and, at the same time, carries lubricant from the reservoir 15 up into contact with the gear teeth of the gear 30, lubricating the latter. The lubricant carried up into the gear 30 drips downwardly into the bearing 12 and then into the space between the bearing sleeve 17 and the depending collar 18, serving 20 thereby to lubricate the bearings.

It will be understood that the above construction is of a typical rotary and that my invention may be applied to rotaries differing from the above in details of construction.

In my invention the lubricant passing through the friction bearings 12 into the bearing space between the sleeve 17 and collar 18 is recovered and returned to the reservoir 15. For this purpose an annular sump is formed below the sleeve 17 by means of an annular ring 31 secured to the bottom edge of the collar 18 by means of screws 32 and having an upwardly extending wall or flange 33 encircling the depending flange 16 of the base 10. Oil or lubricant flowing downwardly through the bearings is thus caught and retained in the annular channel or sump thus formed. When the table 11, and with it the collar 18 and ring 31, rotate, the lubricant in the sump is also caused to rotate and the centrifugal force thus imparted to it causes it to climb or pile up against the upstanding flange or wall 33 until it overflows the upper edge of the wall. This overflow under centrifugal force may be somewhat facilitated by inclining the wall 33 outwardly as shown in Figs. 2 and 3. The lubricant thrown outwardly over the edge of the wall 33 is received in an annular trough 34 mounted on the inner surface of the inner wall 14 immediately below the upper edge of 40 45 50 55

the wall 33 and passes through passages 35 in the wall 34 back into the reservoir 15.

It will be apparent that when the rotation of the table stops, the lubricant will flow downwardly from the upper edge of the wall 33, thus ensuring against overflow and loss of lubricant. The ring 31 may extend outwardly beyond the wall 33 in a flange 36 to lessen or eliminate the splashing of mud upwardly against the trough 34 and wall 33.

Through the above invention a lubricating circuit is provided that is entirely enclosed and protected against the entrance of water or mud in the ordinary course of drilling and in which the loss of lubricant is avoided. The lubricant is free to circulate through all of the bearings without risk of loss. The rotary may, therefore, be run continuously over long periods of time without inspection or filling with lubricants.

20 What I claim is:—

1. A well drilling rotary which comprises a rotary table having a downwardly depending sleeve, a bearing about said sleeve, a lubricant reservoir, gearing for driving said table and carrying lubricant from said reservoir into said bearing, a sump carried by said sleeve below said bearing in position to receive lubricant therefrom and having an upper edge above the liquid level of said reservoir over which lubricant

30 may pass under centrifugal force, and means to convey said overflow lubricant to said reservoir.

2. A well drilling rotary which comprises a rotating table having a downwardly depending sleeve, a bearing about said sleeve, a lubricant reservoir, gearing for driving said table and carrying lubricant from said reservoir into said

bearing, a sump carried by said sleeve below said bearing in position to receive lubricant and having an upper edge above the liquid level of said reservoir but permitting overflow under centrifugal force, a trough encircling said sump and mounted on the inner wall of said reservoir in position below the overflow edge of said sump and communicating with said reservoir.

3. A well drilling rotary which comprises a rotary table having a downwardly depending sleeve, 10 a bearing about said sleeve, a lubricant reservoir, gearing for driving said table and carrying lubricant from said reservoir into said bearing, a sump carried by said sleeve below said bearing in position to receive lubricant therefrom and having 15 an upper edge above the liquid level of said reservoir over which lubricant may pass under centrifugal force, means to convey said overflow lubricant to said reservoir, and a horizontal extension outwardly from the lower edge of said 20 sump to protect said sump against upward splashing of mud.

4. The rotary of claim 1 in which the outer wall of said sump is inclined outwardly.

5. A rotary comprising a rotating table, a bearing for said table, a lubricant reservoir below and outside of said bearing, gearing for driving said table and carrying lubricant from said reservoir into said bearing, and a sump below said bearing and receiving overflow lubricant passing 30 through said bearing, said sump being carried on and rotating with said table and having an upper edge above the liquid level of said reservoir and over which lubricant may be projected by centrifugal force to said reservoir.

AUGUST R. MAIER.
